UNITED STATES PATENT OFFICE

2,545,219

PIVOTED COVER FOR RING WATCHES
AND THE LIKE

S. Alexander Wittmayer, New York, N. Y.

Application September 3, 1946, Serial No. 694,607

2 Claims. (Cl. 58—88)

1

This invention relates to combinations of watches and rings, similar to the one shown and described in my copending application for Combination Ring Watches, Serial Number 646,425, filed February 8, 1946, and has for its main object to provide a pivoted cover for the winding crown of the watch, having a novel spring action closing and opening means incorporated therein.

Another object of this invention is to provide, generally for a recess in a jewelry, or in any other object, a pivoted cover having a novel spring means incorporated therein, whereby the same may be caused to keep both, its open, or its closed position.

A further object of my invention is to provide a novel spring for such pivoted covers, whereby the same may have a stronger spring effect than provided by springs now used for such cases, and whereby the spring may be exchanged without any disturbance to the rest of the mechanism.

Still other objects of this invention will be apparent as the specification of the same proceeds.

In the drawings forming a part of this specification and accompanying the same:

Fig. 1 is a side elevational view of a ring carrying watch to which my invention has been applied, showing said pivoted cover in a closed position;

Fig. 2 is a fragmentary sectional view on an enlarged scale, and

Fig. 3 is a perspective outer detail view, taken as indicated by the arrow 3 in Fig. 2, while

Fig. 4 is another inner fragmentary perspective view, taken as indicated by the arrow 4 in Fig. 2.

Referring now to the drawings more in detail by characters of reference, the numeral 10 indicates my watch ring, in general, being composed of a ring proper part 11, and a generally globular watch case 12 carried thereby, the watch mechanism (not shown) being enclosed in said casing, said casing having a horizontally slidable cover 13, to expose the watch dial when desired, as it is well known in this art, and as has been described in detail in my mentioned copending application.

As it is well known, and has been described in my said application, a winding crown 14 projects from the casing 12, and a pivoted cover, generally indicated by the numeral 15, is provided to normally conceal the winding crown 14. An aperture 16 is hollowed out in the respective left side upper part 11a of the ring 11, which is adapted

2

to receive the lower part 15a of the pivoted cover, when in a closed position.

The inner end 15b of said cover is pivoted on a pin 17 and will have the two rectangularly set operating surfaces 18 and 19. An opening 20 is provided in the bottom of the recess 16 to the inside of the ring, however leaving a supporting surface or plate 21 at the rear bottom part of the recess 16. The upper end 16a of the recess 10 16 is closed by the respective portion 12a of the watch casing wall. A cross bar or pin 22 is arranged in the recess 16 over, but spaced apart from, the bottom rest plate 21.

Threaded between said cross bar 22 and the 15 bottom rest plate 21, I arrange my novel spring 23, its upper end pressing against the watch case wall portion 12a, while its lower end protrudes through the opening 20 in the front part of the bottom of the recess 16.

20 The recess 16 will be wider at its upper end and narrowing towards the lower end thereof, as indicated in Fig. 3, and the spring 23 will have a similar shape converging downwardly, as best indicated in the inner view of Fig. 4. The 25 lower free end 23a of the spring may be quite narrow, and preferably rounded.

The use and operation of my novel pivoted cover, and the spring securing means for the same, will be obvious from the herein description, and the showing of the drawings; still I want to offer the following further explanation:

Normally, the pivoted cover 15 will be in the closed position indicated in Fig. 1, so as to conceal the winding crown 14, the said cover preferably 35 being shaped to provide a part of the ornamental design of the ring. In such a position, the lower end 23a of the spring 23 will act on the surface 19, and by its action will keep the pivoted cover 15 in its closed position.

40 When it is desired to expose the winding crown 14, the lid or cover 15 will be opened up, turning on its pivot pin 17, as indicated by arrow 24, its open position being shown in the Figs. 2, 3 and 4. In this position, the lower end portion of the 45 spring 23 will act on the bottom end surface 18 of the lid 15, as best shown in Fig. 2, and by its action obviously will keep the lid or cover 15 in its said open position.

To again conceal the crown 14, the lid 15 will 50 be moved in a direction oppositely to arrow 24, the spring 23 insuring its steady motion, on the pivot 17 under spring pressure, and acting on the surface 19 to keep the lid in its closed position.

To place the spring into the construction 55 described, all that is needed is to place the same be-

tween the bottom plate 21 and the cross bar 22, its upper end pressing against, and being somewhat curved over, the upper end wall 12a of the recess 16, and then place the lid 15 into position and pivotally secure it by inserting the pin 17 into its place. The pressure of the spring end 23 against the inner end of the lid 15, in combination with the upper and lower supports 22 and 21 for the spring and its upper end pressing against the upper wall 12a, will keep the spring in its operative position without any other securing means.

Similarly, if it is desired to exchange the spring, the pin 17 may be removed, the lid 15 raised, the old spring 23 pulled out of position, and a new one pushed into its place, whereupon the lid 15 may return to its pivoted position. Another method for exchanging the spring 23 might be in making the cross bar 22 in the form of a pin, the end of which will rest in appropriate through-going holes 22a in the side walls of the recess 16, and from between the lower end of the lid 15 and the bottom plate 21, upwardly, and replacing a new one in an opposite manner, pushing it downwardly, whereupon the cross bar 22 may be replaced.

These removing and exchanging operations are particularly efficient when a spring 23 breaks, and in such cases, the parts of the spring obviously can be easily removed, and a new spring inserted.

With present similar pivot springs, when the same become worn or inoperative, or break, a portion of the ring or other jewelry usually must be disturbed to release portions of the spring secured thereinto by soldering, or the like, and the new one also must be soldered in place, so that my device obviously is more practical, requiring less labor, less expense, and entailing less chances of hurting the delicate design or parts of a ring or other jewelry.

I may remark that the said downwardly narrowing shape of the spring 23, the upper wider portion thereof being amply supported in both directions upwardly and downwardly by the watch casing wall 12a, the upper bar 22 and the lower plate 21, will also insure a safer operation for the spring, leading to much longer service thereof, and to less chance of its breaking, while at the same time, the same construction will obviously make the spring action, and pressure of its lower end 23a, much stronger than would be the case if the spring 23 were shaped of equal width, and without being supported in the treble manner herein described and shown.

It is also obvious that my novel spring securing and control means may be applied to other items of jewelry, where it is needed, and generally to any appropriate cases of pivoted lids or covers.

While I have shown a preferred embodiment of my invention, it is to be understood that changes and variations may be resorted to in the elements, combinations, and operation of my invention, and I reserve my rights to such changes

and variations as are within the spirit of this specification, and the scope of the claims hereunto appended.

What I claim as new, and want to protect by Letters Patent, is:

1. In a ring watch, having a ring proper and a housing with a watch mechanism therein secured on said ring, a winding crown projecting from said housing in the plane of the ring, a cover for said crown, a recess in the ring to receive the lower portion of said cover, a pivot for said cover at the lower end of said recess, an extension on the cover beyond said pivot to the inside of the recess, a flat spring placed at the bottom of the recess, the inner end of the spring leaning against the inner end wall of the recess, said bottom having an opening underneath the free outer end of the spring, said outer end of the spring having a tendency for upward pressure and engaging said extension on the cover in such direction, and a transverse bar across said recess, engaging said spring over the intact portion of said bottom, said bar being removable to allow an exchange of the spring without disturbing the rest of the device.

2. In a ring watch, having a ring proper and a housing with a watch mechanism therein secured on said ring, a winding crown projecting from said housing in the plane of the ring, a cover for said crown, a recess in the ring to receive the lower portion of said cover, a pivot for said cover at the lower end of said recess, an extension on the cover beyond the said pivot to the inside of the recess, a flat spring placed at the bottom of the recess, the inner end of the spring leaning against the inner end wall of the recess, said bottom having an opening underneath the free outer end of the spring, said outer end of the spring having a tendency for upward pressure and engaging said extension on the cover in such a direction, a transverse bar across said recess engaging said spring over the intact portion of said bottom, said upper wall of the recess being formed by the watch casing.

S. ALEXANDER WITTMAYER.
